(57) **CLAIM**

We claim the ornamental design for a lighting fixture, as shown and described.

DESCRIPTION

FIG. 1 is a left elevation view showing a first embodiment of any new design of a lighting fixture;

FIG. 2 is a right elevation view of the lighting fixture of the first embodiment;

FIG. 3 is a front elevation view of the lighting fixture of the first embodiment;

FIG. 4 is a rear elevation view of the lighting fixture of the first embodiment;

FIG. 5 is a top plan view of the lighting fixture of the first embodiment;

FIG. 6 is a bottom view of the lighting fixture of the first embodiment;

FIG. 7 is a perspective view of the lighting fixture of the first embodiment;

FIG. 8 is a left elevation view showing a second embodiment of my new design of a lighting fixture;

FIG. 9 is a right elevation view of the lighting fixture of the second embodiment;

FIG. 10 is a front elevation view of the lighting fixture of the second embodiment;

FIG. 11 is a rear elevation view of the lighting fixture of the second embodiment;

FIG. 12 is a top plan view of the lighting fixture of the second embodiment;

FIG. 13 is a bottom view of the lighting fixture of the second embodiment; and,

FIG. 14 is a perspective view of the lighting fixture of the second embodiment.

The broken line disclosure represents portions of the lighting fixture which form no part of the claimed design.
